UNITED STATES PATENT OFFICE.

ROBERT D. KINYON, OF CHICAGO, ILLINOIS.

BARREL-FINISHING MACHINE.

980,967.

Specification of Letters Patent. Patented Jan. 10, 1911.

Application filed March 8, 1909. Serial No. 482,061.

To all whom it may concern:

Be it known that I, ROBERT D. KINYON, a citizen of the United States, residing at Chicago, in the county of Cook and State 5 of Illinois, have invented certain new and useful Improvements in Barrel-Finishing Machines, of which the following is a specification.

My invention pertains to improvements in 10 machines or devices for smoothing or finishing the exterior convex surfaces of barrels, casks, tubs, firkins, and the like, and includes means for smoothing the staves and also subjecting them to the polishing or 15 finishing effect of sand, such as by the employment of a sand-belt or drum.

The main and leading object of the invention is the provision of an appliance of this character which will be both simple 20 in construction and economical to manufacture, the device at the same time possessing the advantage of finishing barrels or the like expeditiously.

In the accompanying drawings, which 25 form a part of this specification and to which reference should be made in connection with the following detailed description, I have illustrated a preferred and desirable embodiment of the invention, and in these 30 drawings—Figure 1 is a front elevation of the appliance with one of the shafts partly broken away; Fig. 2 is a plan view of the machine, certain parts being broken away and others shown in section; Fig. 3 is a 35 vertical section on line 3—3 of Fig. 1, the rasp or planer cylinder shaft being sectioned; Fig. 4 is a face view of one of the supporting and holding heads equipped with independently adjustable cone 40 sections; Fig. 5 is a central section of the construction shown in Fig. 4; Fig. 6 is a 45 central section of the clutch mechanism of the lower shaft; Fig. 7 is a face view and Fig. 8 an edge view of a planer cylinder or head which may be used as a substitute for the rasp illustrated in Figs. 1 to 3, inclusive.

The main frame of the machine includes 50 a pair of parallel spaced wooden beams 10, supported by suitable legs or standards 11, 12 and 13, such beams being cross-connected at intervals by transverse blocks or the like characterized 14, 15 and 16. Supported on the inner faces of the longitudinal beams 10 are a pair of angle-tracks 17 and 18 (Fig. 3) adapted to support a re-

ciprocatory rectangular carriage 19 equipped on its bottom face with bearings 20 accommodating transverse shafts 21, supplied at their ends with rollers 22 adapted to roll 60 or travel on the top, horizontal, inwardly-extended flanges of the angle tracks.

Between the beams 10 and rotatable in suitable bearings 23 and 24 I provide a comparatively long screw-shaft 25, passing 65 through a threaded nut 26 fixed to the bottom surface of the sliding carriage 19, whereby turning of the screw-shaft causes forward or rearward travel of the carriage and parts supported thereby. At its front 70 end shaft 25 has a gear 27, the teeth of which mesh with those of a similar gear 28 on a bottom shaft 29 rotatable in bearings 30 and 31, this shaft having fixed thereon by set-screws 32, as is indicated in Fig. 6, a 75 clutch spool or sleeve 33 supplied at its opposite ends with integral disks 34 and 35 having beveled or chamfered surfaces 36. The sleeve 33 also has at both ends cylindrical recesses or cavities 37 and 38 housing a pair of coil expansion springs 39 and 40. Spring 39 at one end bears against the bottom of the recess 37 and at its other end presses against a face of a pulley 41 loosely mounted on the shaft 29 and having a conical surface 42 adapted to co-operate with a corresponding surface of the disk portion 34. The spring 40 bears against a similar pulley 43 also loose on the shaft 29 and supplied with a conical surface 44 to coact 80 with a similar surface of the disk 35, it being obvious that these springs in the normal conditions of the parts act to separate the two pulleys from the driving clutch sleeve 33 fixed to the shaft. Loose on this shaft I 85 supply a pair of sleeves 45 and 46 each having an annular groove in which fits an inwardly-extended pin of a sleeve actuator or clutch operating member 47, the inner elevated or off-set end 48 of which has a pin 100 49 projecting into slots 50 of the bifurcated arm 51 rigid with a transverse shaft 52 rotatable in a pair of bearings 53 and 54 mounted on the sides of the supporting legs 12. At the front of the machine this controlling shaft has fixed thereto a similar arm 55 having a loose connection with the top end of a link 56 pivoted at its lower end to one leg or section of a double treadle or lever 57, centrally fulcrumed or pivoted at 110 58 and supplied with a pair of foot pieces 59 and 60. Also disposed transversely of

the comparatively heavy frame of the machine I provide a rock shaft 61 having an inner arm 62 loosely connected to the part 48 of the sleeve shifter 47 and supplied at its outer end with a handle 63. A driving belt 64 encircles the pulley 41 to rotate the same in one direction, while a crossed belt 65 encircles the other loose pulley 43 to rotate the same in the opposite direction. It should be apparent, therefore, that by the actuation of either the handle 63 or the treadle 57 either pulley may be shifted lengthwise the shaft 29 into operative frictional engagement with the sleeve 33, whereby one belt or the other 64 or 65 may be caused to rotate the shaft in one direction or the other, such rotation being transmitted through the gears 27 and 28 to the screw shaft 25 and the carriage 19 which it operates.

The rear portion of carriage 19 has mounted thereon a pair of bearings 66 and 67 in which a tail shaft 68 is adapted to rotate and slide, such shaft at one end carrying a tail drum 69 having on one face a plurality of slotted, radially-adjustable, cone-sections 70 adapted to fit in and support a headless end of a barrel, cask, or the like, to be smoothed and finished by this appliance. Each sector or section 70 has a slot 71 accommodating a bolt 72 passing through the drum and acting to clamp or maintain the section in adjusted position, rotation of the latter about the bolt being prevented by the pin 73 rigid with the drum and projecting into the slot 71. Fastened to the standards or supports of bearings 66 and 67 by bolts or other suitable means is a horizontal toothed or notched sector 74 co-operating with which is a sliding, spring-actuated, locking dog 75 of a lever 76 fulcrumed on the frame of the sector at 77 and provided with a slotted strap 78 which permits the lever to straddle a collar 79 fixed to the tail shaft 68 and equipped with a pin 80 projecting into the slot of the strap. It should, therefore, be apparent that by swinging the lever or handle 76 the shaft 68 and drum and cone or beveled sections carried thereby may be slid toward and from the barrel or similar container 81, the parts being capable of being locked in adjusted position by the dog 75 engaging one of the notches of the segment 74.

In aligned bearings 82 and 83 mounted on the cross-supports 15 and 16 a comparatively long head shaft 84 is rotatable and slidable, the shaft being also supported and accommodated by a bearing 85 on the front or head portion of the sliding table or carriage 19. At one side of this latter bearing such shaft is equipped with a rotary disk 86 having on one face barrel supporting, adjustable, cone sections 70 like those indicated in Figs. 4 and 5. This shaft 84 on

opposite sides of the bearing 85 has a pair of collars 87 and 88 fixed thereto which compel this shaft to travel with the carriage, the same sliding in the stationary bearings 82 and 83. A tight pulley 89 is splined on this shaft, the latter being also equipped with a loose pulley 90, both of such pulleys being prevented from partaking of the sliding movement of the shaft by the spacing spools 91 and 92 interposed between the pulleys and the adjacent bearings 82 and 83. A driving belt 93 is adapted to co-operate with either of the pulleys 89 or 90, being shifted from one to the other by a belt shifter 94 operable by a fulcrumed handle 95. The purpose of the shaft 84 is to rotate the barrel during the smoothing operation and throughout the entire length of the sliding movement of the carriage 19, shaft 84 being of sufficient length to accomplish this purpose.

On the top ends of a pair of standards or bent bars 96 and 97, bolted to the outer face of the front beam 10, I adjustably mount a pair of slotted guides 98 and 99 adjustable toward and from the barrel by means of tightening screws 100 engaging threaded holes in the bottoms of the guides and passing through slots 101 in the top, horizontal, outwardly-bent ends of the bars or supporting standards 98 and 99. As is indicated, each of these guides has a horizontal slot 102 accommodating the two bearings 103 of a rasp or planer cylinder shaft 104, such bearings being connected by a loop handle 105, whereby they may be simultaneously shifted in the guiding slots. Between such bearings and guides the shaft 104 is supplied with a cylindrical rasp 106, the shaft being rotated by a pulley 107 mounted thereon and co-operating with a driving belt 108 driven from any suitable source of power such as an upper pulley, not shown. To prevent the bearings 103 from leaving the front open ends of the guiding slots 102 I provide each of the same with an adjustably bent stop 109 partially overlapping or closing the mouths of the slots. To prevent injury to the operator, a sheet-metal shield or cover 110 may be fastened to the guides so as to wholly or partially cover the rapidly rotating rasp. The supports 98 and 99 are secured to the frame of the machine in such position that the rasp will be substantially opposite the left-hand end of the barrel, as indicated in Fig. 2, when the latter is at the extreme right-hand end of its movement.

In a bracket or standard 111, positioned at the back of the machine and substantially opposite the rasp, I place a shaft or rod 112 and loosely mounted thereon, between the two upstanding arms of the bracket, a pulley 113 around which passes a sand belt 114, this belt also passing around an upper

pulley not shown but so positioned that when the front side of the belt, that is the side toward the barrel, is taut, as indicated in dotted lines in Fig. 3, the belt will not be in contact with the barrel positioned in the machine. On this shaft 112 I pivot two arms of a frame 115 carrying two belt-tightener pulleys 116 and 117 located some distance apart, the frame or bracket having a forwardly-extended loop handle 118 provided for the purpose of swinging the frame so as to cause the pulley 117 to deflect the front stretch of the sand belt so as to bring it in contact with the exterior surface of the barrel, it being understood that such bradant belt is sufficiently loose on its pulleys to permit its operation. When the operator releases the handle 118 the frame carrying the pulleys will of its own weight and the action of the belt swing rearwardly about the shaft 112 to the dotted line position indicated in Fig. 3, whereby the pulley 116 deflects the back stretch of the belt, permitting the front stretch to become taut, in which position it is some little distance from the barrel. In order that the bracket 111 and the parts carried thereby may turn or swivel, I provide the same with a cylindrical extension or shaft portion 111^a extending through the back beam 10, the bracket being held in place by a nut 111^b on the lower threaded end of such part.

On the carriage 19 between the drums 69 and 86 I mount a pair of curved, guiding, barrel-supporting rods 119 on which the barrel is adapted to rest before the tail drum is shifted to bring the supporting cone sections in the open ends of the barrel or cask, these rods 119 being so shaped that they guide the barrel toward such cone sections. In order also that the carriage when it reaches its normal forward position indicated in Fig. 2 may actuate the clutch controller 47 to render both clutches inoperative, I pivot at 120 on the front beam 10 a short lever or arm 121 adapted to engage one side of the handle 63 and actuate the same to govern the operation of the clutches.

The operation of this mechanism is practically as follows:—Assuming that the belt 93 is on the loose pulley 90 and that neither of the belts 64 or 65 is acting upon shaft 29 and screw 25, and that the tail drum 69 has been retracted, a barrel with open ends to be smoothed and finished is deposited or rested on the supporting rods 119, whereupon the handle 76 is shifted to the right, bringing the cone sections carried by the disk 69 into the tail end of the barrel, and causing the latter to travel slightly forwardly to receive in its head end the supporting cone sections of the head disk 86. After the barrel is thus securely mounted on and clamped between the two disks and sectional cones, the handle 76 is locked in position to

maintain the parts in this relation, the spring dog 75 entering one of the notches in the stationary segment 74. The operator then actuates the handle 95 to shift the belt from the loose pulley 90 to the tight pulley 70 89, such shifting causing a rotation of the shaft 84 and the barrel held between the disks. The rotation of the barrel having thus been accomplished, the operator either by the handle 63 or by the treadle 57 and 75 foot-piece 59 shifts the clutch controller 47 to the left to render the belt 65 operative to rotate the screw 25 in such direction that the carriage and barrel will be caused to travel toward the left as the device is viewed 80 in Figs. 1 and 2. The workman also grasps the handle 105 and presses the rotating rasp 106 on to the surface of the barrel to effect the smoothing operation as the barrel rotates and travels by the same. Inward and 85 outward sliding of such rasp and its lateral turning, owing to the free movement of its bearings 103 in the guides 102 permit the operator to follow the contour of the barrel as the same travels along. As is well known, 90 the staves of such barrels may not always fit together neatly and are not always smooth on their exterior, the rasp finishing the barrel so that it presents a substantially-smooth exterior. When the barrel has completed its 95 movement to the left, the operator actuates the treadle 57 through the foot-piece 60 so as to shift the clutch controller 47 to cause a reverse rotation of the screw 25, which, as will be readily understood, slides the carriage 19 in the opposite direction. During this travel of the carriage to the right the workman or operator pulls the handle 118 toward him so as to bring the sand belt on to the barrel, shifting such handle and swiveling the bracket 111 as may be necessary to compel the belt to properly follow the contour or convexity of the barrel actuated upon, the rasp during such travel of the barrel having no action thereon. When the 100 carriage and barrel reach the limit of their right-hand movement, the former strikes the lever 121, turning the same on its fulcrum 120 and shifting the handle 63 to render both clutches of the shaft 29 inoperative, 105 110 thereby causing a cessation of the travel of the carriage. By releasing the handle 76 and drawing backward the disk 69, the smoothed, finished barrel or cask may be easily removed and replaced by another, as 115 120 will be readily understood.

In some cases, and especially where second-hand or used barrels are to be smoothed, it is desirable to employ a knife-equipped planer-head or cylinder in place of the rasp shown 125 and described, and in Figs. 7 and 8 I have indicated a suitable construction for this purpose. The cylinder or planer head 122 is provided with a plurality of sharp-edged knives 123 held in place by tightening or set- 130

screws 24 and inclined with respect to the axis of the cylinder. Since such a device operates in substantially the same manner as the cylinder of an ordinary planer, a further description thereof appears to be unnecessary.

Inasmuch as the invention herein set forth is susceptible of a variety of embodiments and is not limited and restricted to the exact structural features herein set out, it may be remarked that many minor mechanical changes may be made in the finishing device of this application and drawings without departure from the substance and essence of my invention, and without sacrificing any of its benefits and advantages.

I claim:

1. In a machine of the character described, the combination of means to rotate a barrel, 20 means to reciprocate the barrel in a straight line during such rotation, a shaft, a smoothing implement mounted on said shaft, means to rotate said shaft and implement, a pair of bearings for said shaft, guides for said 25 bearings in which the latter are adapted to slide, and a handle connected to both of said bearings, whereby the smoothing implement may be moved toward and from the barrel and may be shifted to follow its contour, substantially as described.

2. In a machine of the character described, the combination of a movable carriage, a pair of drums adapted to retain a barrel between them, a pair of shafts mounted upon said carriage, one of said shafts being longitudinally movable with respect to the carriage and attached to one of said drums, the second shaft being also mounted on said carriage and attached to the other drum, means for locking the movable shaft and drum in an adjusted position, means mounted independently of the carriage for rotating the second shaft, means for moving said carriage reciprocatingly, said second shaft retaining a sliding connection with said rotating means, a shaft fixed with respect to the travel of the carriage, a smoothing implement mounted on said shaft, means to rotate said shaft and implement, a pair of bearings for said shaft, guides for said bearings in which the latter 50 are adapted to slide, and a handle connected to both of said bearings, whereby the smoothing implement may be moved toward and from the barrel and may be shifted to follow its contour, substantially as described.

ROBERT D. KINYON.
